UNITED STATES PATENT OFFICE

HENRY S. McGEE, OF MEMPHIS, TENNESSEE

CARD INDEX

Application filed June 19, 1930. Serial No. 462,334.

This invention relates to card indexes of that type which includes a frame having opposed channelways and a plurality of cards interchangeably supported on carriers having ends disposed in said channelways, said cards having an overlapping relation relative to each other, and said cards being pivotally sustained, so that by swinging upwardly the cards above any desired card, the subject matter on said card will be exposed to view, and such card if folded, may be opened out and the matter on such opened portion thereby, be exposed to view. This invention particularly relates to the means whereby a plurality of such frames may be supported for ready inspection of the cards thereon, and whereby any frame may be individually positioned and supported in such manner, that the cards thereon are accessible for detailed inspection and/or for the purpose of making additional entries thereon. This invention further relates to the detail of the sheet carriers, and the means by which they are attached and retained in the opposite guides of the frames.

The objects of my invention are to provide means for supporting a plurality of frames whereby each of said frames may be individually accessible either for casual inspection or for work on the cards carried thereby; and to provide an improved means for supporting and spacing the cards in such frames.

The means by which the foregoing and other objects are accomplished and the manner of their accomplishment will readily be understood from the following specification on reference to the accompanying drawings, in which:

Fig. 1 is a sectional elevation through the frame-support showing a face view of one of the frames with a plurality of card carriers thereon and with cards on a limited number of such carriers, this view also showing an edge view of one of the frames swung into position and supported for work to be done on the cards carried thereby;

Fig. 2 is an enlarged sectional detail taken as on the line II of Fig. 1, showing a frag-

mentary portion of a card carrier unit and its relation to one channel of the frame;

Fig. 3 is a front view of a card carrier;

Fig. 4 is a corresponding side view of the same unit, both of these views being on a somewhat larger scale than Fig. 1;

Fig. 5 is a section on the line V—V of Figs. 3 and 4;

Fig. 6 is a plan view of the frame-support with a plurality of frames supported therein;

Fig. 7 is a corresponding front elevation of the upper portion of the same support and frames;

Fig. 8 is an enlarged fragmentary sectional elevation corresponding to Fig. 1, and showing in dotted lines one of the frames in the first position to which it is moved in placing it for work on the cards; and

Fig. 9 is a fragmentary sectional elevation taken as on the line IX—IX of Fig. 8.

Referring now to the drawings in which the various parts are indicated by numerals, 10 is a frame having outwardly projecting channel shaped sides 11, in which the carrier units are disposed. Each of these units comprises an elongated flat strip of resilient metal 12, having its opposite ends formed into loops 13. These loops 13 are each pro-

vided with a slot 14, the slot of one loop facing that of the other, the two slots being adapted to receive and hold the opposite ends of a straight wire or bar 15 on which a card 16 is hung. In Fig. 2, the loop 13 extends outward from the strip, whereas in Figs. 3 and 4 it extends inward from the end, in either event however, the inner part of the loop is slotted and the outer part limits end-

wise movement of the carrier wires. The wires 15 are resilient, and are flexed to insert the ends thereof in the slots 14 or to remove them from the slots. Each of the carriers thus formed may be sprung into place in the guides 11 and when a number of them are so placed will present a plurality of equally spaced carrier wires on which cards may be supported in similarly equally spaced overlapping relation. Each card may be punched

with holes 17 through which the carrier wires 15 are threaded to support the card or since

90

95

100

the carrier wires are small and have no enlargement on the ends thereof, the cards may be threaded thereon without the necessity of pre-punching holes therein. In either event 5 however, the hole for the carrier wires 15 need be only big enough to pass the wire therethrough, thus avoiding the necessity of punching a hole which might obliterate or interfere with data on the card 10 and at the same time more firmly positioning the card on the wire. A card thus supported is less liable to lateral displacement in the hold and also the hinge effect in swinging the card about the wire is much smoother 15 and there is less liability of hanging or other interference in turning the card.

Any wire may be detached from its holder, a card threaded thereon, and the wire then be sprung back into place firmly securing 20 the card carried thereby in the holder and in the frame by which the holder is supported. Removal of a card is at any time easily effected by merely springing the wire out of its holder. It will be further 25 noted that the carrier wires rest solidly against a part of the frame so that when any card is opened up for the purpose of making an entry thereon, such card rests on a substantially solid backing and there is little or no interference such as is caused where the cards are spaced away from the frame by virtue of the fact that the carrier wires do not lie solidly thereagainst.

When a card has been removed the carrier 30 holder may also be removed and the remaining holders be moved together to close up the gap caused by such removal. Likewise, the carrier holders may be moved apart for the insertion of additional holders in the proper 35 alphabetical or numerical sequence of the cards which they carry.

Ordinarily the carrier holders while readily movable along the channelways to permit such shifting will present sufficient resistance 40 to such shifting to prevent accidental shifting in ordinary use but should this not be found sufficient the lower holder may be readily bowed so that such amount of resistance as may be desired may thereby be secured.

Each of the frames is provided at its upper end with a transverse rod 18, having downwardly turned ends 19 forming vertically disposed hinge pins disposed laterally slightly 45 beyond the sides 11 of the frame. Duplication of the ends is made solely in order that either edge of a frame may be supported whereby each frame may be faced in desired direction. Only one of these pins is used at 50 any one time for supporting a frame. A similar construction may be had at the opposite end of the frame primarily for the purpose of forming a lateral support for the lower end of the frame, but such construction will also 55 avail to invert the frame if it be so desired.

The support for the frames comprises preferably a transverse plate 20, having sides 21 turned out at right angles thereto thus forming in effect a wide shallow channel. Disposed through and supported by these sides is a transverse rod 22 on which rod a number of hinge blocks 23 are disposed. Preferably the space between the sides 21 is just sufficient to snugly receive an even number, twelve being shown, of these hinge blocks. Each hinge block is provided adjacent one end with a horizontal hole therethrough which is adapted to rotatably fit the transverse rods 22, and is also provided adjacent the opposite end with a smaller vertical hole which is adapted to similarly receive a hinge pin 19. Extending transversely across the support-back 20, is an angle shaped bar 24 which supports the hinge blocks 23 in substantially horizontal position. A similar angle bar, disposed near the bottom end of the support-back forms a stop against which the lower ends of the frames abut when they are supported by the hinge blocks.

Each frame may be attached to or detached from a hinge block by merely inserting one of its hinge pins in, or removing it from, the vertical hole of a hinge block. When so hung the frame is maintained in substantially vertical position by such hinge and the lower stop therefor provided. It will be noted by reference especially to Fig. 9, that the transverse rod 18 preferably lies behind the frame 10 with the upper edge of the frame back bent therearound. In such case referring 100 to Figs. 6 and 7, the ends of these bars are preferably bent forward so that the hinge pins 19 are disposed substantially opposite the centers of the sides, or channels 11.

If it be so desired, a cover plate 26 may be 105 hingedly secured at the upper end of each frame 10 as by the pivot pins 27. This cover plate would normally cover the upper cards which were disposed in the frame. It may be turned upward to substantially the dotted 110 position 26-A (Fig. 9) in which position it serves as a shelf against which the upper cards may be turned for making entries thereon.

It will also be seen that the surface of this 115 cover plate when in normal position is substantially flush with the surface of the channelways 11, so that interference with one frame with the adjacent frame by engagement of an edge thereof with the channelway 120 is prevented. At the bottom of the frame a transverse filler block 28 extending from channelway to channelway may be provided for a similar purpose and in addition to this purpose such filler block will absolutely prevent the carrier units from dropping out of the bottom of the channelways 11.

Referring to Fig. 6, it will be noted that one-half of the frames are turned with their faces outward to the right and the remaining 130

half thereof are turned with their faces outward toward the left, those frames which lie on the right preferably facing to the right, whereas those which lie on the left face to the left. In so placing these frames one-half of them use the hinge pins 19, at one side of the frame and the others use the similar pins at the opposite sides of the frame. With the frame so hung should it be desired to casually refer to a card on any frame, the frames to the left thereof are pushed to the left and those to the right thereof are pushed to the right, such shifting to the right being shown in Fig. 6, from which figure also it is evident that if the remaining frames shown were pushed to the left it would be easy to glance at a card in the first frame to the right.

If however, it is necessary to make more extended examination of a card or a number 20 of cards, or if it is desired to make entries thereon, the frame carrying such card may be swung outward about the rod 22 to the dotted position 10—A shown in Fig. 8. The corresponding position of the associated parts 25 being also indicated by affixing the letter A to each designating numeral. With the frame in such position it is turned over about the hinge pin into the horizontal position indicated by the numeral 11—A in Fig. 1, of course with the face side of the frame upward. It will be especially noted that where half of the frames are faced to the left, and half are faced to the right as shown in Fig. 6, the tops of at least one-half the frames form a support for the frame which has been so positioned.

Having described my invention, what I claim is:

1. In a file, a frame-support, a horizontally disposed rod carried thereby, a plurality of hinge blocks mounted on and turnable about said rod, each of said blocks having a hole therethrough at right-angles to and axially spaced from said rod, and a plurality 45 of card-supporting frames, each having a projecting hinge pin engaging a hole in a hinge block.

2. In a file, a frame-support, a horizontally disposed rod carried thereby, a hinge block 50 mounted on and turnable about said rod, said block having a hole therethrough at right-angles to and axially spaced from said rod, and a card-supporting frame having a projecting hinge pin engaging the hole in said hinge block.

3. In a file, a frame-support, a horizontally disposed rod carried thereby, a plurality of hinge blocks mounted on and turnable about said rod, each of said blocks having a hole 60 therethrough at right-angles to and axially spaced from said rod, and a plurality of card-supporting frames, each having a downwardly projecting hinge pin engageable with a hole in a hinge block.

4. In a file, a frame-support, a plurality of

frames each carrying card-supporting devices, universally movable hinges, each connecting an upper end of a frame edge to said support, and a stop carried by said frame support engageable by the lower end of said edge. 70

5. In a file, a frame-support, a frame carrying card supporting device, a universally movable hinge connecting an upper end of a frame edge to said support, and a stop carried by said frame support engageable by the 75 lower end of said edge.

6. In a file, a frame-support, a rod carried thereby, a hinge block mounted on and turnable about said rod, said block having a hole therethrough at right angles to and spaced 80 from said rod, and a card supporting frame having a hinge pin engaging the hole in said hinge block.

In testimony whereof I hereunto affix my signature.

HENRY S. McGEE.
